UNITED STATES PATENT OFFICE.

EDWARD LONGSTRETH, OF PHILADELPHIA, PENNSYLVANIA.

LOCOMOTIVE-ENGINE.

SPECIFICATION forming part of Letters Patent No. 249,962, dated November 22, 1881.

Application filed October 10, 1881. (No model.)

To all whom it may concern:

Be it known that I, EDWARD LONGSTRETH, a citizen of the United States, residing in Philadelphia, Pennsylvania, have invented certain 5 Improvements in Locomotive-Engines, of which the following is a specification.

My invention relates to that class of locomotive-engines in which a truck is combined with one, two, or more driving-axles and one 10 or more pairs of driving-wheels, and in which an equalizing-lever extending from the truck is connected at the rear end to a spring or springs, the object of my improvements, which are fully described hereinafter, being to prevent 15 the rolling or careening of locomotives of this class, which are well known among railroad engineers as "mogul" or "consolidation" engines.

In the accompanying drawings, Figure 1, 20 Sheet 1, is a vertical section of sufficient of a locomotive-engine to illustrate the ordinary mode of construction adopted prior to my invention by the Baldwin Locomotive Works; Fig. 2, Sheet 2, a transverse section on the line 25 1 2; Fig. 3, Sheet 1, a vertical section, illustrating my invention; Fig. 4, Sheet 2, a vertical section on the line 3 4, Fig. 3; and Fig. 5, Sheet 2, a perspective view in which part of one of the main frames is cut away.

30 My improvements may be more readily understood by referring, in the first instance, to the mode of construction practiced prior to my invention and illustrated in Figs. 1 and 2.

There are the usual frames, A A', and three 35 driving-axles, B, B', and B², for three pairs of coupled driving-wheels. The box for the second driving-axle, B', in each frame bears against the under side of the equalizing-lever D, and the box of the third axle, B², against 40 the under side of the equalizing-lever D', these levers being combined with a system of springs too well known and too clearly shown in the drawings to need description. This arrangement of equalizing-levers and spring is the 45 same on both sides of the engine. Each box b of the first driving-axle bears against a spring, F, which is connected at one end to the frame by a strap or link, a, and at the other end to a transverse bar, G, Fig. 2. In like manner 50 the corresponding spring F at the opposite side of the engine is connected at one end to the frame, and at the other end to the same transverse bar G, and this is connected in the middle by a link, I, to one arm of the lever H, the 55 other arm of which is jointed to the lower end of

a rod which passes through the king-post K of the truck W. This truck, which is of well-known construction, is provided with springs for the axle-boxes, as usual, and these springs serve to partially absorb the shocks to which 60 the truck is subjected; but the main shocks are transmitted through the lever H to the springs F F. Locomotives in which the lever H is connected to the springs F F of the boxes of the first driving-axle are apt to careen or 65 roll when running at high speed, and for this reason I have adopted the plan which I will proceed to describe, reference being had to Figs. 3, 4, and 5.

The lever H is connected to the lower end 70 of a link, M, Figs. 4 and 5, which is joined to the strap m of a transverse spring, N, the ends of the latter having their bearings on the opposite frames A A'.

The springs F F have no connection whatever with the lever H, each of these springs being connected at one end by a link, w, to the frame, and at the opposite end by a link, v, to one end of a spring, Y, which bears against the frame, and the opposite end of 80 which is connected to one of the arms of the equalizing-lever D. It will thus be seen that the springs F F of the boxes of the first driving-axle are totally independent of the spring 85 for the truck, the lever H having its own special spring, N, bearing on the frame.

It has been ascertained by practical comparison of locomotives built according to my improvement with those built according to the plan first described and illustrated in Figs. 1 90 and 2, that the objectionable careening or rolling of the locomotive made in accordance with the old plan is obviated by my invention.

I claim as my invention—

1. The combination of the lever H of a locomotive with a spring, N, having its bearing 95 on the frames and independent of the springs of the driving-axle, substantially as set forth.

2. The combination of the lever H of a locomotive with a spring, N, having its bearing on 100 the frames, and the link M, jointed to the strap m of the said spring, substantially as specified.

In testimony whereof I have signed my name to this specification in the presence of two subscribing witnesses.

EDWARD LONGSTRETH.
